UNITED STATES PATENT OFFICE.

JOHN F. HEMENWAY, OF NEW YORK, N. Y.

PRESSURE-ROLL RELEASE FOR CLOTHES-WRINGERS.

1,220,113.

Specification of Letters Patent. Patented Mar. 20, 1917.

Application filed July 26, 1916. Serial No. 111,405.

To all whom it may concern:

Be it known that I, JOHN F. HEMENWAY, a citizen of the United States, residing at New York city, in the county of New York and State of New York, have invented certain new and useful Improvements in Pressure-Roll Releases for Clothes-Wringers, of which the following is a specification, reference being had therein to the accompanying drawing.

This invention relates to certain new and useful improvements in pressure roll release for clothes wringers, the object being to provide a positive release which can be quickly operated in order to instantaneously release the pressure on the pressure rolls.

Another object of my invention is to provide a pressure release which is exceedingly simple and cheap in construction, and one in which a resilient member is employed for holding the pressure means in predetermined position, operating means being provided in connection with said resilient retaining means adapted to move the resilient member into such position that the pressure means will be instantaneously released and held in that position until reset.

Another and further object of my invention is to provide a pressure release in which the movable pin is mounted within the top bar of the wringer frame having a rack formed on the shank thereof adapted to be engaged by a pivoted pawl for holding the pin in adjusted position so as to maintain the resilient member in such position that the pressure will be released on the pressure roll.

Other and further objects and advantages of the invention will be hereinafter set forth and the novel features thereof defined by the appended claims.

In the accompanying drawings,

Figure 1 is a front elevation partly in section showing the application of my improved construction of pressure release thereto.

Fig. 2 is a detail perspective view of the parts constituting the release detached.

Like numerals of reference refer to like parts in the several figures of the drawing.

In carrying out my invention I employ a

wringer frame 1 having slotted side bars in which are mounted superposed bearings carrying pressure rolls 2 and 3 which are of the ordinary construction now in use, the upper bearings being provided with spring supports on which are mounted pressure springs 4 which are engaged by plates 5 carried by a pressure bar 6, said plates being engaged by pressure screws 7 carried by a movably mounted top bar 8 mounted within the slotted portions of the side bars of the wringer frame.

Secured over the upper end portions of the side bars of the wringer frame are members 9 provided with substantially inverted T-shaped slots 10 into which are adapted to extend the end portions of a retaining spring 11 slidably mounted on the under face of the bar 8, said spring being provided with substantially T-shaped ends 12 coöperating with the inverted T-shaped slots 10 in such a manner that when the ends of the spring are drawn inwardly, the stem of the T will be brought into vertical alinement with the reduced portions, or the stems of the inverted T-shaped slots 10, so as to allow the top bar 8 of the wringer frame to move vertically in order to release the pressure on the pressure rolls as will be hereinafter fully described.

The top bar 8 of the wringer frame is provided with a centrally disposed vertical bore 13 in which is mounted a headed pin 14, the shank of which is provided with a rack portion 15 adapted to be engaged by a spring actuated pawl 16 pivotally mounted on the top bar 8, the shape of the pawl and rack being such that the pin is free to move downwardly and is held in its adjusted position by the pawl. The lower end of the pin 14 is rounded and extends below the top bar into the centrally disposed bowed portion 11' of the spring 11 so that when the pin 14 is forced downwardly, the ends of the spring 11 are drawn inwardly so as to bring the stem of the T-shaped heads thereof into alinement with the stems of the inverted T-shaped slots 10 of the members 9 which allows the top bar to move upwardly within the side bars of the wringer frame so as to release the pressure on the pressure rolls, the

upward movement being limited by the length of the slot in the member 9, and the top bar is prevented from becoming detached from the wringer frame by the heads of the spring.

- 5 The construction of pivoted pawl herein shown and described is formed of a blank having depending apertured ears 16' which straddle the top bar 8 and through which a 10 pivotal pin 16² passes for pivotally mounting the pawl in position upon the top bar, said blank having a tail portion 16³ under which is arranged a spring 16⁴ which normally holds the pawl 16 in engagement with 15 the rack 15 of the pin 14 so as to lock the pin in its adjusted position, the pin 14 being free to move downwardly as the pawl rides over the teeth of the rack but is prevented from moving upwardly until the tail 16³ of 20 the pawl is depressed so as to throw the pawl out of the path of travel of the pin which allows the pin to return to its normal position in order to place the top bar into such position of the wringer frame, that 25 proper tension can be applied to the pressure rolls.

While I have shown and described the particular construction of operating member in the form of a pin engaged by a pivoted 30 pawl of a particular construction, I do not wish to limit myself to any particular construction of a slidably mounted operated member and pivoted pawl as various other constructions of operating members and 35 pawls can be used without departing from the spirit of my invention, as the main object to be accomplished is to provide an operating member which can be forced downwardly into engagement with the retaining 40 spring in order to draw the ends of the spring into such position that the top bar will be released, the spring being held in its adjusted position by the pin being locked by the pawl.

45 From the foregoing description it will be seen that I have provided a pressure release for a wringer in which a movably mounted top bar is mounted within the wringer frame and is provided with a slidably mounted 50 spring having T-shaped ends coöperating with T-shaped slots formed in members secured to the side bars so as to hold the top bar in predetermined position within the wringer frame in such a manner that when 55 the operating member which coöperates with the spring is depressed, the ends of the spring will be drawn inwardly so as to release the top bar and allow the same to move vertically within the wringer frame in order 60 to release the pressure on the pressure rolls.

I claim:

1. A clothes wringer, comprising a frame having pressure rolls and pressure means for said rolls, a resilient member having 65 means for normally holding said pressure

means in predetermined position, and a slidably mounted member coöperating with said resilient member for moving and holding said resilient member in position to release said pressure means.

2. A clothes wringer, comprising a frame having pressure rolls and pressure means for said rolls, members carried by the side bars of said frame, a resilient member coöperating with said members, for holding 70 said pressure means in predetermined position, and a slidably mounted member arranged to coöperate with said resilient member for moving and holding said resilient member in position to release said pressure 75 means.

3. A clothes wringer, comprising a frame having pressure rolls and pressure means for said rolls, members carried by the side bars of said frame, a resilient member coöperating with said members for holding said pressure means in predetermined position, a slidably mounted member coöperating with 80 said resilient member for moving said resilient member into inoperative position for releasing said pressure means, and means for holding said slidably mounted member in adjusted position.

4. A clothes wringer, comprising a frame having pressure rolls and pressure means 85 for said rolls, a movably mounted top bar for said frame having pressure screws for adjusting said pressure means, members secured to the side bars of said frame, a resilient member carried by said top bar coöperating with said members for holding said top bar in predetermined position within said frame, a slidably mounted member carried by the top bar arranged to engage 90 said resilient member for holding said resilient member in position to release said pressure means, and means for holding said movably mounted member in adjusted position.

5. A clothes wringer, comprising a frame 110 having pressure rolls and pressure means for said rolls, a movably mounted top bar for said frame having pressure screws for adjusting said pressure means, members secured to the side bars of said frame having 115 substantially inverted T-shaped openings, a spring carried by the top bar of said frame coöperating with said openings, and a slidably mounted member mounted in the top bar of said frame coöperating with said 120 spring for moving and holding said spring in position to release said pressure means.

6. A clothes wringer, comprising a frame having a movably mounted top bar, pressure rolls and pressure means for said rolls 125 mounted within said frame, pressure screws carried by the top bar coöperating with said pressure means, a resilient member carried by the top bar for normally holding said top bar in predetermined position within 130

5 said frame, a pin slidably mounted in said top bar for moving said resilient member in position to release said top bar, and a movably mounted member mounted on the top bar and coöperating with said pin for holding said pin in adjusted position.

7. A clothes wringer, comprising a frame having pressure rolls and pressure means mounted therein, a movably mounted top bar having pressure screws for adjusting said pressure means, a resilient member carried by said top bar for holding said top bar in predetermined position within said frame, a slidably mounted pin carried by 10 the top bar adapted to engage said resilient member, said pin having a rack portion and a pivoted pawl mounted on the top bar coöperating with the rack portion of said pin for holding said pin in adjusted position.

20 8. A clothes wringer, comprising a frame having pressure rolls and pressure means mounted therein, a top bar carrying pressure screws for adjusting said pressure means, members secured to the side bars of 25 the frame having substantially inverted T-shaped openings, a spring carried by the top bar of said frame having substantially inverted T-shaped heads coöperating with said openings, said top bar having a vertically disposed opening, a pin slidably mounted in said opening, adapted to engage said spring, said pin having a rack portion, and a pivoted spring actuated pawl mounted upon said top bar coöperating with said 30 pin, for holding said pin in adjusted position.

9. A clothes wringer, comprising a frame having pressure rolls and pressure means for said rolls, a movably mounted top bar 40 carrying pressure screws for adjusting said pressure means, a resilient member carried by said top bar for normally holding said top bar in predetermined position within said frame, a slidably mounted pin carried by the top bar coöperating with said resilient member for moving said spring in position to release said top bar, said pin having a rack, and a spring pawl mounted upon 45 said top bar coöperating with said rack for holding said pin in adjusted position.

10. A clothes wringer, comprising a frame having pressure rolls and pressure means mounted therein, a movably mounted top bar arranged in said frame having pressure 55 screws for adjusting said pressure means, members secured to the side bars of said frame, a spring carried by the top bar of said frame coöperating with said members for holding said top bar in predetermined 60 position within said frame, a pin slidably mounted in said top bar coöperating with said spring for holding said spring in position to release said top bar, and means for holding said pin in adjusted position.

65 11. A clothes wringer, comprising a frame

having pressure rolls and pressure means mounted therein, a top bar movably mounted within said frame having pressure screws for adjusting said pressure means, members secured to the side bars of said frame having substantially inverted T-shaped openings, a spring slidably mounted on the under side of said top bar having substantially T-shaped heads coöperating with said T-shaped openings, said spring having a central bowed portion, a pin slidably mounted in said top bar above the bowed portion of said spring and adapted to draw the ends of said spring inwardly on the downward movement thereof, and means for holding said pin in adjusted position for holding said spring in position to release said pressure means.

70 12. A clothes wringer, comprising a frame having pressure rolls and pressure means 80 for said rolls mounted therein, a movably mounted top bar carrying pressure screws for adjusting said pressure means, a resilient member for holding said top bar in position within said frame, and a slidably mounted member carried by the top bar of said frame coöperating with said resilient member for moving and holding said resilient member in position to release said top bar.

75 13. A clothes wringer, comprising a frame having pressure rolls and pressure means for said rolls mounted therein, a movably mounted top bar carrying pressure screws for adjusting said pressure means, a resilient member slidably mounted on the under side of said top bar, keepers carried by the side bar for said resilient member, and a slidably mounted member carried by the top bar and coöperating with said resilient 100 member for moving and holding said resilient member in said keepers into position to release said top bar.

105 14. A clothes wringer, comprising a frame having pressure rolls and pressure means 110 for said rolls mounted therein, a movably mounted top bar, pressure screws carried by said top bar coöperating with said pressure means, a spring slidably mounted on the under side of said top bar for holding said top bar in predetermined position, said top bar having a vertically disposed opening, a pin slidably mounted in said opening having its lower end in contact with said spring, the shank of said pin being provided with 115 a rack portion, and a pivoted spring actuated pawl mounted on the top bar coöperating with said rack portion for holding said pin in adjusted position.

120 15. A clothes wringer, comprising a frame having pressure rolls and pressure means for said rolls, a resilient member having means for normally holding said pressure means in predetermined position, a slidably mounted member coöperating with said re- 130

silient member for moving said resilient member in position to release said pressure means, and a spring actuated member coöperating with said slidably mounted member for holding said member in adjusted position.

In testimony whereof I hereunto affix my signature in the presence of two witnesses.

JOHN F. HEMENWAY.
